[57] CLAIM

The ornamental design for an abdomen supporting bodysuit for an expectant mother, as shown and described.

DESCRIPTION

FIG. 1 is a front elevational view of an abdomen supporting bodysuit for an expectant mother showing my new design;

FIG. 2 is a reduced rear elevational view thereof;
FIG. 3 is a left perspective view of FIG. 2, the right side
being a mirror image;

FIG. 4 is a top plan view of FIG. 2; and
FIG. 5 is a bottom plan view of FIG. 2.
